FREDERICK WEINBERG, OF DETROIT, MICHIGAN.

VACUUM-FEED SYSTEM.

1,242,288.

Specification of Letters Patent.

Patented Oct. 9, 1917.

Application filed August 4, 1915. Serial No. 43,507.

To all whom it may concern:

Be it known that I, FREDERICK WEINBERG, a citizen of the United States, residing at Detroit, county of Wayne, State of Michigan, have invented a certain new and useful Improvement in Vacuum-Feed Systems, and declare the following to be a full, clear, and exact description of the same, such as will enable others skilled in the art to which it pertains to make and use the same, reference being had to the accompanying drawings, which form a part of this specification.

My invention relates to vacuum feed systems for internal combustion engines and consist in the improvements hereinafter described and pointed out in the claims.

The accompanying drawing is a vertical elevation, mostly in section, of an apparatus embodying my invention.

10 *a* is an auxiliary tank for receiving the liquid fuel. This tank is divided into two chambers, or compartments, the intermediate reservoir *a*² and vacuum chamber *b*. *c* is a supply tank from which through a conduit 15 *d* liquid fuel is supplied directly to the chamber *b*. The supply conduit or pipe *d* extends through the cover of the tank *a* and terminates in the compartment *b* at a point *e* some distance below the top of said compartment for a reason hereinafter pointed out.

15 *f* is a vacuum pipe communicating with the compartment *b* of the tank *a* at one end and at the other end communicating with a 20 part of the engine, or attachment thereto, so that the motion of the engine shall draw a vacuum through the pipe *f*. In the present instance I have shown the vacuum producing pipe *f* as communicating with a passage 25 in a pet cock *i* which passage extends into the cylinder *g*, but it may communicate with the intake pipe to the engine, as described in my pending applications No. 876,604 and No. 17,141, filed Dec. 11th, 1914, and Mar. 30 26th, 1915.

25 *h* is a carbureter and *m* is a pipe extending from the lower end of the outer compartment *a*² of the tank *a*. The liquid is supplied to the carbureter *h* through the 30 passage *m*.

30 *o* is a float in the compartment *b* of the tank *a*. *p*² is a passage extending from the compartment *b* to the outer air and forming a communication between the exhaust pipe *f* 35 and said compartment. *p* is an outwardly opening valve adapted to close the outer end

of the passage *p*² and in so doing to close the communication between the passage *f* and the outer air. *q* is a rod extending from the float *o* and joined to the valve *p* to raise 60 the same from its seat when the liquid in the compartment *b* has raised a certain height.

*n*² is a passage leading from the lower end of the compartment *b* to the compartment *a*². *n* is a check valve normally open 65 and adapted to automatically close to prevent the flow of liquid from the compartment *a*² to the compartment *b* through the passage *n*².

The movement of this valve is intentionally restricted. It must not be too far from the seat otherwise the comparative small suction would not close it and the device would have to be primed. On the other hand it should be normally open so as to 70 allow the heated fuel to rise from the lower into the upper vessel. The apparatus is necessarily located near the engine and will become heated. The heat expands the fuel and provision must be made to accommodate 75 this expansion, especially immediately after the engine is shut down. The lower vessel is completely filled while the upper vessel is only partly filled and if the valve is open the fuel may rise into the upper vessel and 80 no additional pressure will be exerted against the carbureter needle valve and cause overflow of fuel from the nozzle.

The valve *n* being normally away from its seat will not become attached thereto by 85 adhesion and therefore the trouble that has heretofore been experienced in such devices of the valve sticking to its seat when not in use will be obviated.

j is a small passageway extending through 90 the pet cock *i*. *k* is the plug of the cock *i* adapted to open and close the passage *j*. *f*² is a check valve having a very slight movement and adapted to open toward the passage *j* and to close the passage to the pipe *f* 100 to prevent a flow into said passage from 95 said passage *j*. The passage *f* communicates with the passage *j* in such a way that when a jet or current of gas is forced through the passage *j* it shall create a vacuum therein. 105 When the plug *k* is turned to close the passage *j* the vacuum produced in the cylinder *g* will draw a vacuum in the pipe *f*.

This arrangement is provided to create a 110 vacuum under all existing conditions in pipe *f*. It is a well known fact that by increasing the opening of the carbureter throttle,

the vacuum in the cylinder decreases to such an extent that it can not raise the fluid at a time when it is needed most. For this purpose, extra pumps have been heretofore used.

5 In the present device such vacuum is created by the action of the jet passing through the passage *j* thus a vacuum is created also by the ejector action in the passage *j*.

The pipe *f* is always in communication 10 with the compartment *b* and when a vacuum is drawn in the pipe *f*, a vacuum will also be drawn in the compartment *b* and the pressure of air on the surface of the liquid in the supply tank *c* will force such liquid 15 up through the conduit *d* into the compartment *b* until the level of the liquid in said compartment has risen to such an extent as to force the stem *g* against the valve *p* and force said valve from its seat, which opens 20 the passage *p*² to the outer air and destroys the vacuum in the compartment *b* and passage *f*. When the level of the liquid in the compartment *b* has fallen sufficiently 25 the float *o* will fall and the valve *p* will again close the end of the passage *p*² and the vacuum will again be created in the compartment *b*, as above described. The opening from the tank *b* to the outer air must be large enough relative to that 30 through which the vacuum is drawn so that the vacuum will be freely relieved.

While the supply tank for convenience is shown directly below the tank *a*, in an automobile the tank *c* is located at a considerable 35 distance horizontally from the tank *a* and in the use of an automobile the tank *c* may be raised above the tank *a*, in which case the liquid might flow by gravity into the compartment *b*. To prevent the fluid from 40 flowing out, a valve *q*² is provided around the stem *g*. Said valve being adapted to seat against the valve-seat *q*³ and close the lower end of the passage *p*² so that the liquid will enter the compartment *b*, and 45 the compartment *a* as well, and rise into vent *r*, which leads to a point higher than the highest expected level of fluid in the system. When the tank *c* is again lowered below the tank *a*, there will be a tendency 50 of the liquid in the pipe *d* to run back into the tank *c* and sufficient of the surplus that has been supplied to the compartment *b* will thus run back into the tank *c* so that the valve *q*² will be withdrawn from the 55 valve seat *q*³ and the apparatus will be again in working condition.

What I claim is:

1. In a vacuum feed system, the combination of a vacuum chamber, means for supplying liquid fuel to said chamber because of the vacuum therein, said chamber having an air space and a liquid space, a single air passage leading from the air space of said chamber to the outer air, a vacuum producing 60 passage communicating with said air

passage intermediate of the ends of the latter and a valve adapted to close and open the inner end of said air passage.

2. In a vacuum feed system, the combination of a vacuum chamber, means for 70 supplying liquid fuel to said chamber because of the vacuum therein, said chamber having an air space and a liquid space, a single air passage leading from the air space of said chamber, a vacuum producing passage 75 communicating with said air passage intermediate of the ends of the latter, a valve adapted to close the inner end of said air passage, and a valve adapted to close the outer end of said air passage.

3. In a vacuum feed system, the combination of a vacuum chamber, means for supplying liquid fuel to said chamber because of the vacuum therein, said chamber having an air space and a liquid space, a single air passage leading from the air space of said chamber to the outer air, a vacuum producing passage 80 communicating with said air passage intermediate of the ends of the latter and a valve adapted to close and open 85 the inner end of said air passage, a float in said chamber, said float being adapted to actuate said valve.

4. In a vacuum feed system, the combination of a vacuum chamber, means for supplying liquid fuel to said chamber because 90 of the vacuum therein, said chamber having an air space and a liquid space, a single air passage leading from the air space of said chamber, a vacuum producing passage 95 communicating with said air passage intermediate of the ends of the latter, a valve adapted to close the inner end of said air passage, a valve adapted to close the outer 100 end of said air passage, and a float in said 105 chamber, said float being adapted to actuate said valves.

5. In a vacuum feed system, the combination of a vacuum chamber, means for supplying liquid fuel to said chamber because 110 of the vacuum therein, said chamber having an air space and a liquid space, an air passage extending through the wall of said chamber, a vacuum producing passage 115 communicating with said air passage intermediate the ends of the latter, a rod extending through said air passage and provided with a valve adapted to close the outer end of said air passage, and a valve adapted to close the inner end of said air passage.

6. In a vacuum feed system, the combination of a vacuum chamber, means for supplying liquid fuel to said chamber because 120 of the vacuum therein, said chamber having an air space and a liquid space, an air passage 125 extending through the wall of said chamber, a vacuum producing passage communicating with said air passage intermediate the ends of the latter, a rod extending through said air passage and provided with 130

- a valve adapted to close the outer end of said air passage, a valve adapted to close the inner end of said air passage, and a float in said chamber, said rod being operatively connected with said float.
7. In a vacuum feed system, the combination of a vacuum chamber, means for supplying liquid fuel to said chamber because of the vacuum therein, a separate vacuum producing passage communicating directly with said chamber, an internal combustion engine cylinder having a combustion chamber, said vacuum producing passage communicating directly with said combustion chamber, and a non-return valve located in said vacuum producing passage closing toward said vacuum chamber and opening toward the combustion chamber.
8. In a vacuum feed system, the combination of a vacuum chamber, means for supplying liquid fuel to said chamber because of the vacuum therein, a vacuum producing passage communicating with said chamber, an internal combustion engine cylinder having a combustion chamber, a passage other than the intake and exhaust passages leading from the combustion chamber of said cylinder to the outer air, said vacuum producing passage communicating with the passage from said cylinder, and a non-return valve located in said vacuum producing passage closing toward said vacuum chamber and opening toward the combustion chamber.
9. In a vacuum feed system, the combination of a vacuum chamber, means for supplying liquid fuel to said chamber because of the vacuum therein, a vacuum producing passage communicating with said chamber, an internal combustion engine cylinder having a combustion chamber, a passage other than the intake and exhaust passages leading from the combustion chamber of said cylinder to the outer air, said vacuum producing passage communicating with said passage from said cylinder, a cock in the last named passage outside of the point of communication of said vacuum producing passage with the same, and a non-return valve located in said vacuum producing passage closing toward said vacuum chamber and opening toward the combustion chamber.
10. In a vacuum feed system, the combination of a vacuum chamber, a main fuel supply tank, a conduit connecting said tank and chamber, said tank being normally located below the level of said chamber but liable to be raised above said chamber, a passage leading from said chamber, a float in said chamber forming an operative part of said system when the level of the liquid in said chamber is within certain limits and
- adapted to close said passage when said liquid level raises above said limits, said conduit opening into said chamber at a level within said operating limits for the purpose described.
11. In a vacuum feed system, the combination of a main fuel supply tank, a vacuum chamber, an internal combustion engine having a cylinder and a piston adapted to reciprocate therein, said cylinder being connected by a separate conduit, other than the intake and exhaust conduit to said engine, with said vacuum chamber so that the up and down movement of the piston shall create a vacuum in said vacuum chamber for the purpose of raising the fuel from said main tank.
12. In a vacuum feed system, the combination of a main fuel supply tank, a vacuum chamber, an internal combustion engine having a cylinder and a piston adapted to reciprocate therein, said cylinder being provided with a passage opening upon the suction and compression side of said piston for one or more cycles, and a vacuum producing passage connected with the first named passage so that the jet of air passing therethrough shall produce a vacuum in the vacuum passage.
13. In a vacuum feed system, the combination of a vacuum chamber, a main fuel supply tank, a conduit connecting said tank and chamber, said tank being normally located below the level of said chamber but liable to be raised above said chamber, a passage leading from said chamber, a float in said chamber forming an operative part of said system when the level of the liquid in said chamber is within certain limits and adapted to close said passage when said liquid level raises above said limits, said conduit opening into said chamber at a level within said operating limits, a reservoir adapted to be supplied by gravity from said vacuum chamber, and connected with a vent pipe leading to a point above the highest expected point of the level of the liquid in the system.
14. In a vacuum feed system, a vacuum chamber, means for supplying liquid fuel thereto, a reservoir adapted to be supplied with fuel from said chamber, a conduit extending from said chamber to said reservoir, the delivery opening of said conduit being bounded by a surface forming a valve seat, and a valve pivoted to said surface above said opening so as to normally hang away from said surface, said surface slanting away from said valve, and away from the vertical, downwardly.

In testimony whereof, I sign this specification.

FREDERICK WEINBERG.
